(57) **CLAIM**

The ornamental design for a toe cap for athletic footwear equipment, as shown and described.

DESCRIPTION

FIG. 1 is an isometric view of a toe cap for an athletic footwear equipment, including without limitation in-line skates and ice skates, in accordance with the present invention as viewed from the front and side, looking downwardly on the invention;

FIG. 2 is an isometric view of the present invention shown in FIG. 1, but taken from the bottom of the present invention;

FIG. 3 is a top plan view of the present invention shown in FIG. 1;

FIG. 4 is a bottom view of the present invention shown in FIG. 1;

FIG. 5 is a front elevational view of the present invention shown in FIG. 1;

FIG. 6 is a side elevational view of the present invention shown in FIG. 1;

FIG. 7 is a rear elevational view of the present invention shown in FIG. 1; and,

FIG. 8 is a side elevational view of the present invention shown in FIG. 1, taken from the opposite side of the invention as shown in FIG. 6.
